Primary Examiner — Michael A. Pratt*Assistant Examiner* — Wendy Arminio(74) *Attorney, Agent, or Firm* — Berkeley Law & Technology Group, LLP(57) **CLAIM**

The ornamental design for a cap, as shown and described.

DESCRIPTION

FIG. 1 is a top and front perspective view of a cap showing our new design;

FIG. 2 is a front elevational view of FIG. 1;

FIG. 3 is a back elevational view of FIG. 1;

FIG. 4 is a right side elevational view of FIG. 1;

FIG. 5 is a left side elevational view of FIG. 1;

FIG. 6 is a top plan view of FIG. 1;

FIG. 7 is a bottom plan view of FIG. 1;

FIG. 8 is a bottom perspective view of FIG. 1; and,

FIG. 9 is an isometric view of the cap shown in a position of use on an unclaimed cup drawn in broken lines.

The broken lines in FIG. 9 represent environmental subject matter and form no part of the claimed design.
